UNITED STATES PATENT OFFICE.

PHILIP GANZHORN, OF CHICAGO, ILLINOIS.

KNIFE.

1,375,501.

Specification of Letters Patent.

Patented Apr. 19, 1921.

Application filed May 22, 1918. Serial No. 236,069.

To all whom it may concern:

Be it known that I, PHILIP GANZHORN, a citizen of the United States, residing at Chicago, in the county of Cook and State of Illinois, have invented certain new and useful Improvements in Knives, of which the following is a specification.

This invention relates to improvements in knives for meat choppers. One object is to provide a knife of very simple construction that is cheap to manufacture and efficient in operation. A further object is to provide a knife comprising a simple form of holder wherein novel blade securing and adjusting means are provided. With the foregoing and other objects in view the invention consists in the combination and arrangement of parts to be hereinafter fully described, pointed out in the appended claim and illustrated in the accompanying drawing which forms a part of this specification and in which—

Figure 1 is a fragmentary plan view of my improved knife.

Fig. 2 is a cross section taken on line 2—2 of Fig. 1.

Fig. 3 is a plan view of one type of blade employed.

Fig. 4 is a plan view of a slightly modified form of knife from that illustrated in Fig. 1.

Fig. 5 is a cross section taken on line 5—5 of Fig. 4.

Fig. 6 is a plan view of the blade employed in Fig. 4.

Fig. 7 is a cross section taken on line 7—7 of Fig. 9.

Fig. 8 is a perspective view of the blade holding and adjusting means shown in Figs. 1 and 2.

Fig. 9 is a fragmentary plan view of a slightly modified form of knife.

Like reference characters denote corresponding parts throughout the several views.

My improved knife comprises a holder having a circular hub 1 formed with the central perforation 2 and radiating from said hub are the integral arms 3 which are each formed with a longitudinal slot 4 to receive the blade 5. The arms shown in Figs. 1, 2,

50 7 and 9 are each formed with a perforation 6 upon one side of the groove 4 to receive a screw 7. The screw 7 shown in Figs. 1 and 2 extends entirely through and beyond the perforation 6, the threaded end of said screw

extending beyond the perforation and carrying a nut 8 formed with a stem 9 adapted for insertion in a perforation formed in the blade 5 whereby said blade is releasably retained in operative position in the said groove 4. It is evident that the blade may be secured more or less firmly in the said groove by means of the said screw 6 which is adjustable through the medium of a wrench applied to its head.

In Figs. 7 and 9 the perforation 6, in arm 3, opens into a groove 10 that receives the collar 11 of screw 7, said collar extending beyond the said groove 10 for engagement with the elongated perforation 12 formed in the blade 5. The screw 7 being formed with the groove 13 may be adjusted relatively to the arm 3 to cause adjustment of the blade 5 and to bind the same firmly in the said groove 4.

In Figs. 4 and 5 each arm 3 is formed with a perforation 14 that extends transversely of the groove 4 to receive a screw 15 which engages with a perforated portion in the blade 5 whereby said blade is releasably locked in position in the groove 4.

What is claimed is:

In a knife of the character described, the combination with a substantially rectangular supporting arm having a longitudinal slot in one side face and a transversely disposed centrally located perforation above said slot 85 at right angles thereto; of a reversible blade with longitudinal cutting edges beveled in reverse directions, either edge being adapted to be positioned in said slot, said blade having a central perforation therein, a bolt extending through the perforation of said supporting arm, one end of said bolt projecting out over said blade above the perforation therein, a blade retaining nut threaded on said projecting end of the bolt, and a peripheral radial stem on said nut to be received in the perforation of said blade, the inner end of said slot serving to limit the inward travel of the blade.

In testimony that I claim the foregoing 100 as my own I have hereto affixed my signature in the presence of two subscribing witnesses.

PHIL GANZHORN.
